MULTIPLE NEEDLE TUFTING MACHINE

Joe C. Cobble, Chattanooga, Tenn., and George B. Muse, Sugar Valley, Ga.

Application January 24, 1941, Serial No. 375,716

2 Claims. (Cl. 112—79)

Our invention relates to tufting machines and more particularly to tufting machines for simultaneously forming a series of tufted rows of stitches in a fabric or backing.

Heretofore in making tufted bed spreads, rugs, and mats wherein a great many parallel lines are employed to set in the background, after which flowers or other designs may be superimposed upon them, it has been the practice to form these parallel lines by a series of operations of a single or double needle machine progressively traversing or scanning the backing until the desired surface is covered. These many operations greatly increase the time required to make the article and consequently the resulting cost of production. Furthermore, the distance between the rows of stitches varies over a wide range according to the judgment of the operator and uniformity is accordingly difficult or impossible to attain.

It is true that some efforts have been made to provide a multiple needle tufting machine to accomplish these purposes. However, the number of needles possible in those cases was limited by the load the needle bar was able to take and was further limited by the fact that no effective feeding means had been developed to serve more than a few needles, and no means had been provided for keeping the cloth spread out taut while being fed to the machine in order to insure that the lines of tufts would be uniformly spaced and to keep the cloth from becoming clogged up and torn in the machine. It will be apparent, of course, that such a problem is not serious in single or double needle machines for the operator can keep the cloth spread out taut with her hands over the small area being sewed.

Applicants with a knowledge of all these defects in and objections to the prior art have for an object of their invention the provision of a multiple needle tufting machine which is capable of forming the entire background of parallel lines in a single operation.

Applicants have as another object of their invention the provision of a multiple needle tufting machine having a feed mechanism for progressively passing a whole section of cloth through the machine and forming tufts in it.

Applicants have as another object of their invention the provision of a plural needle tufting machine having a mechanism for spreading a section of cloth as it is fed to the machine for tufting.

Applicants have as a further object of their invention the provision of a plural needle tufting machine having a plurality of loop holding and

severing devices acting in synchronism and actuated from a single shaft for catching the loops in the successive rows to clip them and form tufts.

Applicants have as a still further object of their invention the provision of a multiple needle machine which automatically and continuously feeds long sections of cloth therethrough and forms tufts therein.

Other objects and advantages of our invention will appear in the following specification and accompanying drawings and the novel features thereof will be particularly pointed out in the annexed claims.

In the drawings, Fig. 1 is a front elevation of our improved machine. Fig. 2 is an elevation of one end of the same machine. Fig. 3 is a detail of the work feed mechanism for progressively moving the fabric through our machine. Fig. 4 is a fragmental elevation of the opposite end of said machine. Fig. 5 is a fragmental cross sectional view taken along line 5—5 of Fig. 1.

Referring in detail to the drawings showing the preferred embodiment of our invention 1, 4 and 2, 3 designate the spaced standards comprising the ends of the frame of our improved machine bridged at their lower ends by bases 10, 10 formed from oppositely disposed angle irons providing sockets between them for reception of the lower ends of standards 2, 3 and 1, 4. Joining the upper ends of standards 1, 4 and 2, 3 are angle irons 118, 118. Bridging the ends of the frame adjacent their upper extremities are front and rear frame members 6, 7 of angular configuration which rest upon the angle irons 118, 118 at their ends.

Mounted on the frame and supported in a series of spaced bearings 26, 26 carried by angles 118, 118, 121, 121, bridging the front and rear frame 6, 7, and extending longitudinally of the frame and on beyond its ends is a drive shaft 24 having a pulley 22 mounted thereon for coaction with a plurality of V belts 21 (in the present case three) for transmitting power from a source of power 19 through pulley 20 and shaft 25 to the drive shaft 24.

The source of power 19 may either be an A. C. or D. C. motor of preferably other than the A. C. synchronous type. The motor is supported on a plate 119 through bolts 120 carried by one or more supports 18 of angular configuration joined to standards 2, 3 preferably adjacent their upper ends.

Mounted on the drive shaft 24 at intervals are a series of spaced eccentrics 31, 31. Carried by

each of these eccentrics 31 is a needle bar actuating rod 32 being joined to the eccentric through a split bearing which encircles the outer surface thereof and includes a strap portion 30 joined to the rod through conventional studs.

Mounted on the end of drive shaft 24 near pulley 22 is a wheel 23 to turn it by hand. Mounted on the drive shaft 24 on the other side of pulley 22 is an eccentric 29 carrying a rod 27 mounted similarly to rods 32 heretofore described. This rod is joined through a rocker arm 54 to supplemental shaft 55. Mounted on the outer face of arm 54 through screws 104, 104, carried by it and coacting with recesses formed in the ends thereof is a strap 102.

Mounted adjacent the opposite end of shaft 24 is a pulley 106 for transmitting power through a belt 107 to pulley 108 which rotates shaft 48. Mounted on the end of shaft 24 adjacent pulley 106 is an eccentric 29 which carries rod 28 through a bearing and strap 30 identical to those heretofore described. The opposite end of rod 28 forms a bearing for rotatably mounting pivot pin 57 which may be rigidly secured in adjusted position in slot 59 by a screw thread and nut connection or otherwise to rocker arm 58 mounted on supplemental shaft 55 by means of set screws 60.

Bridging standards 3, 4 and 1, 2 intermediate their ends and secured thereto are work support members 8, 9 of an angular configuration overlapped by a throat plate 44 extending along the entire length of the support members, and having needle slots therein.

Positioned beneath the work support is the supplemental shaft 55 mounted in end bracket bearings 61 having ears for resting upon the upper surface of transverse supports 17, 17 forming part of the frame and bridging standards 2, 3 and 1, 4 and joined to them. The brackets 61, 61 being secured to the supports 17, 17 by studs 62 passing through the brackets and screw threaded into the supports.

Mounted in spaced relation along the supplemental shaft 55 are a series of loopers, the lower ends of whose arms are divided into opposite clamping portions 82, 83 joined through studs 84 which freely pass through strap portion 83 and screw thread into portion 82 for rigidly clamping the looper about supplemental shaft 55. The looper arm is comprised of adjustable members 82, 71, the portion 82 having a longitudinal groove 81 extending upwardly therewith for reception of a longitudinal rib formed on the inner face of portion 71. The upper portion 71 having a longitudinal slot formed therein to permit the free passage of screw 79, which threads into the lower portion 82, to lock the upper portion 71 in adjusted position, thereby permitting the looper to be moved with respect to the work support to vary the length of the nap of the tufts, and for other purposes. To the upper end of upper member 71 is secured a hook 75 of hardened steel through screws 76 (one of the screws being omitted for clarity) which pass through openings in the hook portion and coact with screw threaded openings in the upper member 71. The hook 75 is of hardened metal, has a shoulder adjacent its free end to prevent removal of the loops and a cutting edge extending rearwardly therefrom to coact with a cutting edge on the cutter. The hook 75 is accordingly removable and replaceable.

Extending rearwardly from the upper part of the upper member 71 is a portion having an opening therethrough for the reception of a pivot bolt 75

71 for pivotally supporting a cutter having a forwardly extending arm terminating in a socket for the reception of a blade 72 having an enlarged slanting upper cutting edge for coaction with the cutting edge of the hook 75. The blade 72 is adjustably mounted in the socket by means of the slot 73 in the cutter arm and the screw 74 passing freely therethrough and seating in a screw threaded opening in blade 72. Upon loosening the screw 74 the blade may be moved up and down into adjusted position, since the slot 73 permits free movement of the screw 74 therein. The cutter also has a depending portion 70 joined to a link 67, through a pivot screw 69 carried by the lower depending portion.

Depending from the lower surface of member 8 at intervals therewith are supports 63 and bridging the supports 63, 63 extending along the length of the machine and secured thereto is a block 64 for mounting a series of spaced slidably adjustable fingers 65 by means of screws 66 passing through slots in these fingers, and their ends are joined to links 67 by screws 68. The free ends of the fingers are turned downwardly for gripping to facilitate adjustment of the fingers when the screws 66 are loosened.

Tensioning the cutter against the looper is a spring loop 80 having one end seated in a recess in the cutter and the other end seated in a recess 30 in the looper.

Positioned above the work support or bed plate and in spaced relation to each other are a series of needle bars 35, 35 carried by a channel member 5 bridging the rear standards 3, 4 of the frame and carried by them. Spaced brackets 36, 36, one above the other, bolted on member 5, by bolts 37, serve as bearings for each needle bar 35 and permit its reciprocation therein. The upper end of each needle bar 35 is joined to a corresponding rod 32 by a pivot pin having a shank 112 which acts as a pivot and a shoulder 113 on its outer end which serves as an abutment, the end of the shank 112 terminates in a split socket 33 with portions adapted to be clamped about the needle bar by means of a clamping bolt 34. The opposite end of the needle bar 35 is joined to a needle block which bridges the various needle bars and has longitudinal bores formed centrally therein providing a socket beneath each needle bar to receive a needle 40 and having a set screw 39 seated transversely therein for clamping each needle 40 in its socket. To one side or in front of each needle socket is a second longitudinal bore 38 to permit the free passage of thread therethrough.

Suspended from channel member 5 by means of a plurality of spaced straps 42, 42 is a presser foot 41 having a plurality of spaced openings to permit the free and ready passage of needles 40 therethrough. Each strap 42 has a slot therein for reception of a mounting screw 43 for seating the channel member 5 in order to permit relative movement of the strap upon loosening of the screw 43, the walls of the slot being movable on the bolt 43.

Mounted on and projecting rearwardly from the lower flange of channel member 5 are a series of supporting brackets 90 joined thereto through studs 100 and terminating at their free ends in bearings or other appropriate means for fixedly supporting bar 97.

Mounted on bar 97 in spaced relation are a series of rings 98 disposed about the bar and locked thereto by set screws 99. Each of the rings 98 carries a spring finger 89, preferably

one to each needle, which terminates in a curved end for frictional rubbing engagement with the periphery of a disk 86 having angularly projecting teeth.

Mounted on the rear projections of the transverse supports 17 are upstanding bearings 87, 87 joined to the supports 17 through studs 88, 88. Rotatably mounted in these bearings is feed shaft 85. Freely rotatable on shaft 85 is arm 91 carrying a pawl 94 pivoted thereon at 92 and pressed by spring 93, extending about the pivot 92 and seated in the arm 91 with the free end thereof pressing upon the upper edge of the finger 94, into engagement with the teeth of a ratchet wheel 95 also mounted on shaft 85. The arm 91, intermediate its ends, is pivotally joined through link 101 to arm 54, 102 by pivots 96, 103. As heretofore indicated disks 86 are mounted in spaced relation on feed shaft 85 through set screws 117 and turn with that shaft. Mounted beneath the ratchet wheel 95 on standard 3 by means of bracket 106 is a retarding finger or pawl 105 pivoted on pin 107 on bracket 106 and spring pressed or otherwise urged into yielding engagement with wheel 95.

On the front projections of transverse members 17, 17 are mounted bearings 47, 47 which carry the shaft 48, heretofore referred to. Carried by the shaft 48 and extending substantially the whole distance between bearings 47, 47 is a roller 49 having formed on its outer surface oppositely directed sets of helical ribs 50, 50 which terminate in a point of intersection 51 at substantially the center of the roller 49.

Situated in front of the frame is a seat 11 supported by arms 12, 12 extending horizontally forward from the standards 1, 2 at points below the bed plate. Extending down diagonally from the horizontal arms 12, 12 to the standards 1, 2 are braces 13, 13 which are joined both to the arms 12, 12 and the standards 1, 2. Bridging the arms 12, 12 of the seat is a cloth guide 52, and positioned beneath the seat is a stand 14 carrying a cloth guide 53. The stand has supporting sides 15, 15 with a cover 14 over it. The guide rod 53 bridges the sides at the inner end, and the inner ends of the sides are preferably positioned between the angle irons of the base 10 of the frame.

The cloth 116 is carried in the roll 114 on shaft 115 and is preferably paid off of the roll onto the floor where it then passes up under cloth guides 53, 52 and then over roll 49 which ordinarily rotates in a counterclockwise direction and acts as a spreader. The cloth then passes across the work support or bed plate and throat plate 44, between the feeding disks 86 and the spring fingers 89, and back to the floor.

The thread 111 is fed to the needles through openings in projection 110 on the cross member 6, then down through the conventional tensioning devices 109 which consist of spring pressed opposed plates that receive the yarn and resist its movement. Then it passes down under thread guide 46, which is a bar extending across the front of the machine and supported on standards 1, 2, and on through bore 38 and then to the needle 40.

There may be many appropriate braces for the frame such as that designated 16.

In its operation the drive shaft 24 receives its power from source 19, which, viewed from the source of power end, causes it to rotate in a counterclockwise direction imparting a counterclockwise rotation to shaft 48, an oscillating

movement to supplemental shaft 55, and an intermittent clockwise rotation to feed shaft 85 when viewed from the same end.

The fabric or backing 116 is manually paid off of roll 114 on to the floor, is passed about guides 53, 52 and over spreader 49 across the bed plate or work support into engagement with the teeth of disks 86 and between the disks 86 and the resilient fingers 89 that urge the fabric into intimate, interlocking engagement with the disks 86 so that thus anchored the fabric 116 is progressively moved across the bed plate of the machine, and onto the floor on the other side.

The rotation of drive shaft 24 and in turn eccentrics 31 causes the needle bar actuating rods 32 to reciprocate the needles 40 up and down through the fabric 116 as it moves across the bed plate in a manner well known to those skilled in the art. As the needles pass down through the fabric 116 they carry with them the strands of yarn 111. Upon reaching the lowermost position of their stroke and again starting their upward movement, slack develops in the strands of yarn. The supplemental shaft 55 then oscillates to swing the loopers toward the needles 40 and pass their hooks 75 between the needles and their strands of yarn and catch them to form loops. The cycle is again repeated and a second loop is thrown on the hook so that as the needle is drawn up out of the fabric it is moved through the machine by the feeding disks 86 and fingers 89. The supplemental shaft 55 oscillates back in the opposite direction swinging the loopers back out of the planes of the paths of the needles 40, which movement results in the cutters being swung about their pivots 71 and the blade 72 being brought into cutting relation with the looper hooks 75 clipping the innermost loops to form piles. This operation is repeated over and over again to form rows of stitches.

It will be noted that the spreading roller 49 which acts on the cloth before it reaches the needles 40 rotates the two sets of opposed continuous helical ribs which engage the cloth and tend to spread it from the center towards either outer edge thus removing the wrinkles and holding it smooth and stretched out taut as it passes under the needles 40. This insures that the rows of stitches formed in the fabric will be straight and uniform and prevents the possibility of clogging of the cloth in the machine and the possibility of tearing or injuring thereof.

It will also be understood that the presser foot may be adjusted towards and away from the fabric by loosening the screws 43 and permitting the straps 42 and the walls of their slots to move with respect to the studs 43, after which they may be tightened and the presser foot held in adjusted position.

As already indicated in a general way the rod 27 actuated by an eccentric 29 on shaft 24, substantially identical to that on the opposite end of the shaft for actuating rod 28, causes the expandable rod to reciprocate or oscillate and impart through link 101 the same swinging movement to arm 91 which in turn moves the pawl 94 back across the teeth on ratchet wheel 95 and causes it to index with those teeth and to intermittently rotate the ratchet wheel 95 and feed shaft 85, their movement being synchronized with the needles 40 to take place when such needles are up out of the fabric. The toothed disks 86 being keyed to the shaft 85 by means of set screws 117 move with it. The teeth on these disks being turned in the direction of their

rotation and away from the needles 40 and from the backward force of resistance created by the friction of the backing 116, anchor themselves in the cloth and move it through the machine. In order to insure close contact of the backing or fabric 116 with the teeth of the disks 86 the resilient fingers 89 yieldably urge the fabric against the outer periphery of these disks 86 and their tension may be adjusted by loosening the set screw, rotating the ring, and then tightening it again. By yieldably holding the cloth or backing 116 against the surface of disks 86 over a substantial periphery thereof with the curled ends of fingers 89 ample force is provided for moving it through the machine and any great positive backward force will not result in tearing or injuring the backing but will permit it to yield and slip. This eliminates the use of a vast number of feed dogs under the bed plate of the machine which would raise difficult problems in attempting to actuate them, cause them to act effectively, and to remain synchronized.

It will also be seen that the loopers and cutter attachments utilize the known principle of causing the movement of the looper carrying the cutter pivoted thereon intermediate its ends and having its lower end 70 joined to a fixed point, to impart a swinging movement to the cutter in the opposite direction to that of the looper, thereby bringing them into cutting relation, and it should be pointed out that the throat plate 44 has the usual large and/or elongated needle slots therein to facilitate the removal of the tufts after they are formed, as well as the fact that the openings in the body of the hook portion of the looper through which the screws 76 are enlarged permit some adjustment of the looper with respect thereto and alter the cooperation and relation of looper to cutter for changing the movement of uncut loops and the time of severance in forming the piles. Of course, this may also be controlled and altered to some extent by the adjustment of blade 72 in its socket by loosening screw 74 and moving it in the slot 73.

It will also be understood that applicants' invention is not limited to the use of a ratchet wheel and pawl for actuating the feed mechanism but that any other appropriate means for producing the intermittent motion may also be employed. Applicants have in mind particularly that an over-running clutch mechanism may be substituted for the ratchet wheel and pawl, which has actually been tried and proven to be successful in one of applicants' machines, and is probably preferable to the ratchet mechanism disclosed in the preferred embodiment of applicants' invention by the drawings herein.

Having thus described our invention, we claim:

- 15 1. A multiple needle tufting machine of the character described comprising work feed means for progressively moving a fabric through the machine including a series of toothed disks over which the fabric is trained, yieldable fingers for pressing the fabric into gripping engagement with the teeth of said disks, a series of reciprocating needles for passing strands of yarn down through the fabric to form loops, means positioned beneath the fabric to catch and hold the loops, and means for cooperation with the loop holding means to sever the loops and form tufts.
- 20 2. A multiple needle tufting machine of the character described comprising work feed means for progressively moving a fabric through the machine including a series of disks having ratchet teeth on their peripheries over which the fabric is trained, spring fingers partially surrounding the peripheries of said disks adapted to yieldably hold the fabric in gripping engagement with the teeth of the disks, a series of reciprocating needles for passing strands of yarn down through the fabric to form loops, means positioned beneath the fabric to catch and hold the loops and means for cooperation with the loop holding means to sever the loops and form tufts.
